TO THE NATIONAL CASH REGISTER COMPANY, OF DAYTON, OHIO, A CORPORATION
OF MARYLAND

SPEED CONTROL SWITCH FOR CASH REGISTERS

Application filed November 23, 1925. Serial No. 70,964.

This invention relates to speed control mechanism for cash registers and like machines.

The object of this invention is to provide a means for controlling the speed of operation of power driven cash registers.

With this and incidental objects in view, the invention consists of certain novel features of construction and combinations of parts, the essential elements of which are set forth in appended claims and a preferred form or embodiment of which is herein-after described with reference to the drawings which accompany and form part of this specification.

Of said figures:

Fig. 1 is a view of the speed control mechanism, and the mechanism of a cash register with which it cooperates.

Fig. 2 is a detail view in side elevation of part of the speed control mechanism.

Fig. 3 is a detail view, partly in section, showing the mechanism for opening the control switches.

Fig. 4 is a detail view of part of the mechanism shown in Fig. 3.

Fig. 5 is a detail view of the starting switch.

Fig. 6 is a diagram of the control circuit.

Fig. 7 is a detail view of a part of the motor stopping mechanism shown in Fig. 1.

In general

In power driven cash registers, particularly those which are driven by means of an electric motor, the accumulated speed of the machine on a series of rapidly successive operations may be so great as to damage some of the parts of the machine. This excessive speed is due to the fact that the armature will not come to rest, if the machine is released and a current applied to the motor immediately after the completion of the previous operation. In order to overcome this, a mechanism has been provided which automatically opens a switch in the circuit through the motor, after the machine has reached home, and holds it open for a predetermined length of time thereafter, sufficient to permit the armature of the motor to

either stop or slow down to such an extent that its momentum will be greatly reduced.

This device is herein shown attached to a machine of the type shown in the copending application of Bernis M. Shipley, Serial No. 687,305, filed January 19, 1924. This device is particularly important in a machine of this type, it being an itemized receipt printing machine in which operations are performed in rapid succession. However, it is apparent that the device can be used with any other type of machine of this class, not being limited for use in connection with itemized receipt printing machines.

In detail

Driving mechanism.—Suitably mounted in the frame work of the machine is a cam shaft 30 (Fig. 1), to which is secured a gear 31 meshing with a gear 32 secured to a gear 33 mounted on a stud 29 carried by the frame work of the machine. The gear 33 meshes with a pinion 34 which forms a part of a clutch mechanism of the type shown and described in the Letters Patent of the United States issued to C. F. Kettering and W. A. Chryst, No. 1,144,418, June 29, 1915. No detailed description of the clutch mechanism is herein given as reference may be had to this patent. The clutch connects the pinion 34 to a gear meshing with a bevelled pinion 35 secured to a gear 36 meshing with a pinion 37 secured to the armature 38 of the motor.

The motor is started by closing a switch in a circuit through the motor shown in Fig. 6. This switch comprises a resilient blade 45 and a contact plate 46 (Figs. 5 and 6) suitably mounted on a bracket 44. Cooperating with the switch blade 45 is an arm 47 which is connected to an arm 48 by a cross bar 49. The arms 47 and 48 are pivoted on a shaft 50 suitably mounted in the frame work of the machine. The arm 48 is provided with a roller 51 which cooperates with a disk 52 forming a part of the above mentioned clutch mechanism. The disk 52 normally tends to rotate in a clockwise direction due to a spring 53, one end of which is connected to a stud 54 mounted on the

disk 52 and the other end of which is connected to a stud 55 carried by the other member of the clutch mechanism. Mounted on the disk 52 is a block 56 which is held in contact with an arm of a lever 57 (see also Fig. 1) when the machine is home. When the machine is released by means to be hereinafter described, the lever 57 is rocked on the shaft 58 by a spring 59 to remove it from the path of the block 56 and thereby permit the spring 53 to rotate the disk 52, which by means of a cam edge 65 thereon, will rock the arms 47 and 48 clockwise and press the blade 45 against the contact plate 46. This will close the circuit (Fig. 6) through the driving motor, and, by means of the pinion 37 (Fig. 1), gear 36 and the clutch mechanism, will rotate the pinion 34 in a clockwise direction, which movement will be transmitted to the gear 31 on driving cam shaft 30 by means of the intermediate gears 32 and 33. In this manner, the drive shaft 30 is given one complete rotation at each operation of the machine, near the end of which rotation, a stud 60 (Fig. 7), mounted on a disk 61 fast with the cam shaft 30 wipes along the surface 62 on the right hand end of the lever 57 and rocks the left hand end thereof into the path of the block 56, thereby permitting the switch blade 45 to spring away from its contact blade 46 to open the circuit, and in so doing, rock the arms 47, 48 to their normal positions shown in Fig. 5.

Releasing mechanism.—Mounted on the lever 57 (Fig. 1) is a stud 66 which contacts the upper end of one arm 67 of a bell crank when the machine is in its home position. The bell crank is journaled on the shaft 30 and has a rearwardly projecting arm 68 to which is pivoted the lower end of a link 69. The upper end of the link 69 is pivoted to an arm 70 secured to a shaft 71. Also secured to the shaft 71 is an arm 72 which has mounted thereon a flattened stud 73 held in contact with a trip pawl 74 by a spring (not shown) which normally tends to rotate the shaft 71 in a clockwise direction. Pivoted to the pawl 74 is a link 75 which is also pivoted to an arm 76. The arm 76 is bifurcated to engage a stud 77 mounted on a sliding plate 78. The plate 78 is provided with slots 79 by means of which the plate is mounted on studs 80 carried by one of the frames of the machine. Also mounted on the plate 78 are studs 81 upon which a motor bar 82 is detachably mounted.

The machine is released by depressing the motor bar 82, thereby sliding the plate 78 inwardly. This movement of the plate 78 will rock the arm 76, which, by means of the link 75, will swing the pawl 74 away from the stud 73, thereby permitting the above mentioned spring (not shown) to rock the shaft 71 and arm 72 in a clockwise

direction. Clockwise movement of the shaft 71 will lower the link 69 to shift the arm 67 from beneath the stud 66, which will permit the spring 59 to rotate the lever 57 to disengage it from the block 56, as above described.

The above releasing mechanism is fully shown and described in the above mentioned Shipley application, and therefore, no further reference thereto is thought necessary herein.

Speed control mechanism.—As above mentioned, on repeat operations, if the circuit through the motor is again closed before the momentum of the armature due to the previous operation has spent itself, the speed of the next succeeding operation may be excessive and in any event, rapidly successive operations of the machine will result in gradually accelerating the speed of rotation of the armature to the detriment of the machine. Such gradual building up of momentum occurs more particularly in the armatures of series wound motors. In order to prevent a second operation of the machine before the armature has either ceased its rotation, or the momentum thereof has nearly spent itself, another switch has been provided in the motor circuit, together with a means cooperating therewith, to hold the switch open long enough to permit the armature of the motor to either come to rest, or to permit the momentum thereof to become nearly exhausted.

Meshing with the gear 31 on the driving cam shaft 30 is a pinion 90 loosely mounted on a stud 91 carried by the frame work of the machine. Meshing with the pinion 90 is a gear 92 mounted on a stud 93. The gear 92 meshes with a gear 94 mounted on a stud 95. The studs 93 and 95 are carried on a plate 89 (Figs. 1 and 2) carried by the frame work of the machine. This plate is shown by dot and dash lines in Fig. 1 because it is in front of the mechanism shown therein. Mounted in the gear 94 is a stud 96 (Figs. 1 and 4) to which is attached one end of a clock spring 97, the other end of which is connected to a stud 98 mounted on a cam plate 99 secured to a gear 100 journaled on stud 95 beside the gear 94. The cam plate 99 is provided with a laterally projecting shoulder 101 (Fig. 2) which is held in contact with a lateral lug 102 on a disk secured to the gear 94, by the spring 97 when the machine is in its home position.

Pivoted on a stud 103 (Figs. 1 and 3) is a pawl 104 having an arm 105 which is held in engagement with a stud 106 carried by the gear 92 by means of a spring 107 when the machine is in its home position. The nose 108 of the pawl 104 is adapted to be moved into the path of the shoulder 101 on the cam plate 99 immediately after the machine starts to operate.

Rotation of the gear 31 by the motor, as above described, rotates the gear 92 in a clockwise direction by means of the pinion 90. When the gear 92 begins to rotate, the stud 106 thereon will be disengaged from the arm 105 of the pawl 104, thereby permitting the spring 107 to rock the nose 108 into the path of the shoulder 101. Rotation of the gear 92 rotates the gear 94 in counter-clockwise direction to wind up the flexible drive spring 97, and cam plate 99 and the gear 100 secured thereto, will be carried with the gear 94 by means of the clock spring 97 which holds the shoulder 101 in contact with the shoulder 102. Shortly after the machine starts to operate, the shoulder 101 will contact and be arrested by the nose 108 of the pawl 104, which prevents further rotation of the cam 99 and gear 100. Since the gear 94 carrying the lug 102 is driven by the gear 92, it will continue to rotate and in this manner it will wind up the spring 97. Substantially, at the end of the operation of the machine, the stud 106 on the gear 92 will again engage the arm 105 of the pawl 104, and will rock the arm 108 thereof away from the shoulder 101, thereby releasing the cam plate 99, permitting it to rotate under the influence of the spring 97 until it catches up with and contacts the lug 102 of the gear 94 which arrests further rotation of the gear 100 and the train connected therewith.

One arm of a bell crank switch 116 (Fig. 1) journaled on a stud 115 projecting from the frame plate 89 carries a contact 117 insulated therefrom and adapted to engage between two contact lips 118 mounted on a bar of insulating material fastened to the frame plate 89. The contact 117 and contact lips 118 form part of the motor circuit, as shown in Fig. 6.

A roller 120 mounted on the remaining arm of the bell crank switch 116 is yieldingly held by a spring 121 against the cam disk 99.

When the parts are in their normal or home positions, the roller 120 lies in a low portion or recess 122 of the cam disk 99, with the contact 117 embraced between the contact lips 118 to complete the circuit at this point.

As the machine starts an operation, and the gear 94 rotates to wind up the flexible driving connection or spring 97, the spring turns the cam disk 99 and gear 100 as heretofore explained, the low portion or recess 122 being of sufficient extent to permit the switch 116 to remain in its normal position while the cam disk is being rotated through the direct drive from the gear 92 and during the time when the cam disk and its gear 100 are held against rotation by the locking pawl 104.

But, as soon as the locking pawl 104 is tripped, and the cam disk 99 and gear 100

are freed to the action of the wound clock spring 97, the disk 99 turns to bring an unmutilated portion of its periphery beneath the roller 120 and rocks the switch 116 to open the motor circuit between the contacts 117, 118.

It will be remembered that the cam 99 is not released until nearly the end of the operation of the machine. The rotation of the cam 99 under the influence of the wound spring 97 takes place after the machine has come to rest at the end of an operation, and therefore, the circuit through the driving motor will be automatically held open for such length of time after the machine comes to rest in its home position, as it takes the spring 97 to turn the cam disk 99 to bring the low portion 122 of the cam beneath the roll 120 of the switch 116. From this it can be seen that if, at this time, the operator should depress the motor bar 82, to trip the clutch and effect engagement of the switch blade 45 with the contact 46, the circuit will not yet be completed as the switch contacts 117 and 118 are held disengaged by the unmutilated periphery of the cam disk 99. This circuit will remain open until the cam 99 reaches its home position and the roller 120 of the switch 116 is again rocked into the depressed portion 122, whereupon the contacts 117 and 118 are again engaged.

To prevent the spring 97 from unwinding too rapidly, and thereby defeating the object of this invention which is to delay the closing of the automatic switch 116 until the motor armature has had time to come to rest, a governor is provided to retard the speed of rotation of the gear 100. Meshing with the gear 100 is a pinion 123 secured to a gear 124. The gear 124 is mounted on a stud 125 carried by the plate 89, and meshes with a pinion 126 secured to a fly governor 127. The governor 127 is rotatably mounted on a stud 128 also mounted on the plate 89, and comprises a plurality of vanes 129, each of which is provided with a resistance blade 130.

From the above description it is apparent that when the cam disk 99 is released to be operated by the spring 97, the governor 127 will be rotated by the pinions 123 and 126 and the gear 124, and, as above stated, the blades 130 will provide enough resistance to this train of mechanism to prevent the spring 97 from being unwound too rapidly.

Briefly, assuming the machine to be at rest, as in Fig. 1, with the motor circuit closed at the contacts 117, 118, and open at the contacts 45, 46 (Figs. 5 and 6), the motor idle, and the clutch held disengaged by the detent lever 57, the operator, after setting up on the keyboard the amount to be registered, depresses the starting key 82.

As heretofore explained, depression of the

starting key trips the dog 74 freeing bell crank 67 to the action of its spring (not shown) which rocks the bell crank 67 to release the detent lever 57, whereupon spring 59 rocks the detent lever from the path of the abutment 56 on the cam disk 52 secured to one member of the clutch mechanism.

Thereupon, the spring 53 (Fig. 5) drives the cam disk 52 clockwise to turn the cam 10 and cause it to rock the lever arms 48, 47 to press the spring contact 45 against contact blade 46 to complete the motor circuit (Fig. 6).

Substantially simultaneously therewith, 15 the clutch members engage and the motor positively drives the train of gears leading from the drive gear 34 to the gears 92 and 94 to operate the machine, and wind up the clock spring 97.

20 At the beginning of its rotation, gear 92 withdraws the pin 106 from the arm 105 of the arresting bell crank 104, whereupon spring 107 snaps the nose 108 of the bell crank into the path of the shoulder 101 on 25 the cam disk 99. Gear 92 rotates gear 94 and the lip 102 in counter-clockwise direction (Fig. 1) and in so doing, winds up the spring 97, which, because of its connection with the cam disk 99, turns the cam disk 30 and its gear 100, as fast as the gear 94 and its lip 102 permit, since the spring 97, through the cam disk 99, presses the shoulder 101 against the lip 102.

The gear 94, cam 99 and gear 100 continue to rotate together until the shoulder 101 strikes and is arrested by the nose 108 of the arresting bell crank 104, which obstructs the farther rotation at this time, of the cam disk 99 and gear 100. The positive drive from the gear 34, however, continues to turn the gear 94 and hence winds the spring 97 more tightly as the motor continues to turn, until near the end of the operation of the machine, the stud 60 (Figs. 45 1 and 7) on disk 61 when about completing a full rotation, contacts the end 62 of the detent lever 57 and rocks it into normal effective position against the tension of its spring 59, the opposite end of the detent lever then 50 lying in the path of the abutment 56 on one of the clutch members.

Immediately thereafter, the motor in rotating the clutch, brings the abutment 56 into contact with the end of the detent lever 55 which arrests farther rotation of the clutch member 52 and effects the disconnection of the clutch in a manner well known in the art, the spring 53 (Fig. 5) being tensioned at that time, preparatory to advancing the 60 clutch member 52 on the next operation.

The clutch member 52 is arrested at the time when its low point or recess is beneath the roller 51 of the make-and-break lever 48, 47, whereupon the resilience of spring contact 75 45 rocks the make-and-break lever 48,

47 to enter the roller 51 in the recess in clutch disk 52, which permits the spring contact arm 45 to withdraw from its co-acting contact 46 and interrupt the motor circuit at this point.

70 The motor armature, however, continues to rotate idly.

Substantially simultaneously with the arrest of the clutch member 52, the pin 106 on gear 92 in completing its rotation, trips the 75 bell crank dog 104 and holds the dog in tripped position.

80 Removal of the dog from the path of the shoulder 101 frees the cam disk 99 and its gear 100 to the action of the wound spring 97 which immediately rotates the cam disk 99 and gear 100 counter-clockwise until the shoulder catches up with and is arrested by contact with the lug 102 which is held against advance at this time by the train 85 of gears and the detent lever 57 as well as by the load of the machine on the cam shaft 30.

90 The automatic switch 116 normally maintains the motor circuit closed at the contacts 117, 118, the roller 120 of the automatic lever 116 lying in the elongated depression in the cam disk 99, even when the cam disk is advanced counter-clockwise from the position shown in Fig. 1 to the position wherein 95 the shoulder 101 on the cam disk 99 contacts the detaining dog 104, but immediately at the beginning of the rotation of the cam disk 99 by the spring 97 after the detaining dog 104, releases the cam disk, an unmutilated part of the cam disk 99 rides under the roller 120 to rock the automatic switch lever 116 and interrupt the motor circuit at the contacts 117, 118.

100 At this time, the motor circuit is interrupted at two different points, but may be closed at one of such points by depression of the starting key 82. However, such action would not complete the circuit, which remains interrupted until the cam disk 99 as it reaches the end of its independent rotation, brings its low point 122 beneath the roller 120 on the automatic switch lever 116, whereupon the spring 121 snaps the contact 117 between the contact lips 118 to complete the motor circuit at this point.

110 And it is to extend the period during which the contacts 117, 118 remain separated that the fly 127 is geared to the cam disk 99.

115 While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a machine of the class described, the combination with a driving motor, and a switch for closing a circuit through the motor to enable said motor to operate the machine, of another switch in the same circuit and adapted to temporarily render said first mentioned switch ineffective for a predetermined length of time after the machine completes its operation. 10
2. In a machine of the class described, the combination with a driving motor, driving connections between the motor and the machine, a switch for closing a circuit through the motor to enable said motor to operate the machine, and means for simultaneously stopping the machine and causing said switch to open, of another switch in said circuit, and means operated after the operation of the machine is completed to hold said second mentioned switch open to prevent a subsequent operation of the machine for a predetermined length of time. 20
3. In a machine of the class described, the combination with a driving motor, driving connections between the motor and the machine, a switch for closing a circuit through the motor to enable said motor to operate the machine, and means for simultaneously stopping the machine and causing said switch to open, of another switch in said circuit, and a spring actuated means adapted to be released as the machine reaches its home position to open said second mentioned switch, and hold it open for a predetermined length of time. 30
4. In a machine of the class described, the combination with a driving motor, driving connections between the motor and the machine, a switch for closing a circuit through the motor to enable said motor to operate the machine, and means to simultaneously arrest the machine and enable said switch to open, of another switch in said circuit, a spring actuated cam to control the last-mentioned switch; means to arrest the cam, and means actuated as the machine reaches its home position to release said cam to open said switch and hold it open for a predetermined length of time. 40
5. In a machine of the class described, the combination with a driving motor, driving connections between the motor and the machine, a switch for closing a circuit through the motor to enable said motor to operate the machine, and means to simultaneously arrest the machine and enable said switch to open, of another switch in said circuit, a spring actuated cam to control the last-mentioned switch, a spring for actuating said cam, means to store power in said spring during the operation of the machine, and means to enable said spring to operate the cam to open said switch and hold it open for a predetermined length of time. 50
6. In a machine of the class described, the combination with a driving motor, driving connections between the motor and the machine, a switch for closing a circuit through the motor to enable said motor to operate the machine, and means for simultaneously stopping the machine and enabling said switch to open, of another switch in said circuit, a spring actuated cam, to control the last-mentioned switch, a spring for actuating said cam, a shoulder on said cam, a pawl cooperating with said shoulder for causing said spring to be wound up, and means adapted to disengage said pawl from said shoulder, thereby releasing said spring to permit it to rotate said cam for opening said second mentioned switch and holding it open for a predetermined length of time. 60
7. In a machine of the class described, the combination with a driving motor, a circuit for said motor, and a switch for closing said circuit, of another switch for preventing said first mentioned switch from becoming effective for a certain length of time, a spring actuated cam for opening said second mentioned switch, and a governor for controlling the action of said cam. 70
8. In a machine of the class described capable of successive operations, the combination with a driving motor in circuit with a source of power; driving connections between the motor and the machine; a switch to close the circuit through the motor to enable the motor to operate the machine; and means to enable the switch to open the circuit at the end of each operation of the machine; of a second normally closed switch in circuit with the motor; and means to open the second switch and to hold it open a sufficient length of time to permit the motor to come to rest after the circuit has been opened at the first-named switch. 80
9. In a machine of the class described capable of successive operations, the combination with a motor; a source of power in circuit with the motor; driving connections between the motor and the machine; a manually tripped normally open switch in circuit with the motor; and means to automatically arrest the machine and open the manually tripped switch at the end of an operation of the machine; of a normally closed switch in circuit with the motor; means to close the second-named switch; and means operable automatically to open the normally closed switch substantially simultaneously with the automatic opening of the normally open switch. 90
10. In a machine of the class described, capable of successive operations, the combination with a motor; driving connections between the motor and the machine; a normally open, manually tripped switch in circuit with the motor; and means to automatically arrest the machine, and open the man- 100

ually tripped switch at the end of an operation of the machine; of a normally closed switch in circuit with the motor; means to close the last-named switch; a power-storing means driven by the motor; means to trip the power-storing means for operation; and means operated by the power-storing means to open the last-named switch and hold it open temporarily, until the switch-closing means can operate.

10 11. The combination with a motor; a normally open, manually tripped switch in circuit with the motor; drive means operated by the motor; and means to automatically open the manually tripped switch; of a normally closed switch in circuit with the motor; means to close the last-named switch; a separate motor; means to free the separate motor for operation; and means operated by the last-named motor to automatically open the last-named switch, and to hold it open until the switch-closing means can operate.

15 12. The combination with a motor; a normally open, manually tripped switch in circuit with the motor; drive means operated by the motor; and means to automatically open the manually tripped switch; of a normally closed switch in circuit with the motor; means to close the last-named switch; a spring-motor wound by the first-named motor, a detent to enable the spring-motor to be wound; means operated by the first-named motor to trip the detent; and means operated by the spring motor to automatically open the last-named switch, and to hold it open until the switch-closing means can operate.

20 13. The combination with a motor; a normally open, manually tripped switch in circuit with the motor; drive means operated by the motor; and means to automatically open the manually tripped switch; of a normally closed switch in circuit with the motor; means to close the last-named switch; a cam disk to control the last-named switch; a spring to drive the cam disk when the motor circuit is opened at the first-named switch; a detent to prevent operation of the cam disk by the spring; means operated by the motor to trip the detent to enable the spring to rotate the cam to open the last-named switch, and to hold such switch open temporarily.

25 14. The combination with a motor; a normally open, manually tripped switch in circuit with the motor; drive means operated by the motor; and means to automatically open the manually tripped switch; of a normally closed switch in circuit with the motor; means to close the last-named switch; a separate motor; means controlled by the first-named motor to free the last-named motor for operation; means operated by the last-named motor to open the last-named

switch, and to temporarily hold such switch open; and means to retard the speed of operation of the last-named motor.

In testimony whereof I affix my signature.
